CONVERSION OF HYDROCARBON OILS

Jean Delattre Seguy, Chicago, Ill., assignor to
Universal Oil Products Company, Chicago, Ill.,
a corporation of Delaware

Application May 10, 1933, Serial No. 670,375

6 Claims. (Cl. 196—49)

This invention particularly refers to an improved process and apparatus for the conversion of relatively high-boiling hydrocarbon oils for the production of high yields of lower boiling products wherein the raw oil charging stock is first subjected to relatively mild conversion conditions, high-boiling and low-boiling conversion products arbitrarily separated, the low-boiling products subjected to more severe conversion in a conjointly operated cracking system while said high-boiling conversion products are subjected to less severe conversion conditions than those imposed upon the low-boiling products in the same conjointly operated cracking system.

15 A more specific embodiment of the present invention may comprise subjecting a relatively high-boiling hydrocarbon oil such as heavy crude petroleum, topped crude, fuel oil or the like to relatively mild conversion in a heating coil, introducing the heated oil into a vaporizing chamber wherein the low-boiling products, comprising a substantial proportion of the gas oil produced, are separated from the higher boiling products which remain unvaporized in this zone, subjecting a portion of said low-boiling products to more severe conversion conditions of elevated temperature and superatmospheric pressure in a separate heating coil, introducing the heated oil into a separate vaporizing chamber, preferably maintained at substantially reduced pressure relative to that employed in the heating coil, wherein the vaporous and residual conversion products are separated, subjecting the vapors to fractionation whereby their insufficiently converted components are condensed as reflux condensate, subjecting fractionated vapors of the desired end-boiling point to condensation, collecting the resulting distillate and gas, returning reflux condensate produced by fractionation of the vaporous conversion products to the last mentioned heating coil for further conversion, together with said low-boiling fractions from the first described cracking operation, and commingling the unvaporized high-boiling fractions from the first described cracking operation with the hot conversion products passing from the last mentioned heating coil to the reduced pressure vaporizing chamber.

20 The present invention permits the ultimate conversion of relatively high-boiling oils into high yields of desirable low-boiling products, such as motor fuel of high anti-knock value, without the excessive production of undesirable products such as coke and gas and also permits a flexibility of operation whereby intermediate prod-

ucts, such as gas oil of the desired quality may be recovered, when desired, as well as permitting the production, when desired, of good quality residual oil, suitable, for example, as fuel. By use of the two-stage method of conversion provided by the present invention, the first or relatively mild stage produces high yields of intermediate oils, such as gas oil, for further conversion in the second stage to produce high yields of good quality motor fuel. More severe conversion conditions may be employed for the production of the motor fuel in the second stage than permissible, without excessive yields of coke and gas, in the conversion of higher boiling oils such as supplied to the first cracking stage of the process. By this method of operation a product of better motor fuel characteristics, particularly with respect to anti-knock value, may be produced than could be accomplished by cracking the heavy charging stock in one operation. Also by the method of operation of the present invention the high-boiling products of the first cracking stage are subjected to further conversion under milder conversion conditions than those employed for the treatment of lower boiling products, whereby additional yields of good quality motor fuel and minimum yields of coke and gas are produced.

25 Other advantages and features of the present invention will be more apparent with reference to the accompanying diagrammatic drawing and the following description thereof. The drawing illustrates one specific form of apparatus embodying the features of the present invention and the description of the drawing includes a more detailed description of the operation of the process as it may be practiced in the apparatus illustrated.

30 Referring to the drawing, the raw oil charging stock to be treated is supplied through line 1 and valve 2 to pump 3 by means of which it is fed through line 4 and valve 5 to heating coil 6 wherein it is subjected to the desired relatively mild conversion temperature, preferably at superatmospheric pressure, by means of heat supplied from a furnace 7 of any suitable form.

35 The charging stock may of course, be pre-heated when desired in any well known manner, not illustrated, prior to its introduction into heating coil 6. The hot conversion products are discharged from heating coil 6 through line 8 and valve 9 into vaporizing and separating chamber 10 which may be operated at substantially the same pressure as that maintained at the outlet from heating coil 6 but is preferably operated at reduced pressures in order to assist vaporiza-

tion. The vapors from chamber 10, comprising the low-boiling conversion products and preferably including a substantial proportion of the products within the boiling range of gas oil, pass 5 through line 11 and valve 12 to condensation in condenser 13, the condensate being withdrawn therefrom through line 14 and passing, in part, when desired, through valve 15 in this line to storage or to any desired further treatment. 10 However, at least a portion of this product is preferably diverted from line 14 through line 16 and valve 17 to pump 18 by means of which it is fed through line 19, passing preferably, all or in part, through valve 20 in this line into fractionator 21 or, when desired, from line 19 through line 22, valve 23 and line 24 direct to heating coil 25.

Ordinarily, although relatively mild conversion conditions are preferably employed in heating coil 6, some materials within the boiling range of gasoline will normally be produced in the first conversion stage of the process and these will vary in quality and quantity with the nature of the charging stock and the conversion conditions 20 to which it is subjected. When this motor fuel product is of good character it may be collected, together with the other motor fuel conversion products of the process of similar end-boiling point, by supplying the distillate from condenser 25 18 to fractionator 21, as previously described. However, when these fractions of the distillate product from chamber 10 are of inferior motor fuel quality, particularly with respect to their anti-knock value, the distillate may be supplied 30 directly to heating coil 25, by means already described, wherein it may be subjected to further conversion under conditions suitable to effect a substantial improvement in its anti-knock value.

Line 26 containing valve 27, communicating 40 through line 16 with pump 18, permits the introduction of suitable oil from any desired external source to the second cracking stage of the process. This oil from an external source, which may be considered secondary charging stock, preferably 45 comprises an oil similar in cracking characteristics to the distillate from the first and previously described cracking stage of the process and may be supplied, all or in part, either to fractionator 21 or to heating coil 25 or, in part, 50 to both, as described in connection with the introduction of the distillate from condenser 13 into this portion of the system. The low-boiling charging oil for the second cracking stage of the process, when supplied to fractionator 21, as illustrated and described, serves to assist fractionation 55 of the vaporous conversion products with which it is directly commingled in the fractionator by means of which the charging stock is preheated. Any charging stock introduced into fractionator 21, as well as vaporous conversion products supplied to this zone, boiling above the end-boiling point of the desired overhead stream of fractionated vapors comprising the light distillate product of the process, are condensed as 60 reflux condensate within the fractionator and collect within its lower portion from which they are withdrawn through line 28 and valve 29 to pump 30 by means of which they are supplied through line 24 and valve 31 to heating coil 25, 65 70 commingling, in line 24, with any charging stock supplied thereto through line 22 and valve 23, as previously described.

Heating coil 25 is located within a furnace 32 of any suitable form, by means of which the oil 75 supplied to the heating coil is brought to the de-

sired conversion temperature, preferably more severe than that employed in heating coil 6 and preferably at a substantial superatmospheric pressure. The heated oil is discharged from heating coil 25 through line 33 and valve 34 into vaporizing chamber 35, which is preferably maintained at a substantially reduced pressure relative to that employed at the outlet from the heating coil, accomplished by the manipulation of pressure control valve 34, whereby the heated 10 conversion products are cooled and their vaporization in chamber 35 assisted.

Simultaneous with the introduction of heated oil from heating coil 25 into chamber 35, the high-boiling conversion products from heating 15 coil 6 which remain unvaporized in chamber 10 are withdrawn therefrom through line 36 and valve 37 to pump 38 by means of which they are fed through line 39 and valve 40 into line 33, commingling therein with the highly heated oil 20 from heating coil 25, serving to cool the hot conversion products further than that accomplished by reduction of the pressure imposed thereon, the heavy oil from chamber 10 being thereby heated to a milder conversion temperature than that 25 employed in heating coil 25.

Residual oil remaining unvaporized in chamber 35 may be withdrawn therefrom through line 41 and valve 42 to cooling and storage or to any desired further treatment. The vaporous conversion products pass from chamber 35 through line 43 and valve 44 to fractionation in fractionator 21 wherein their insufficiently converted components are condensed and returned, as previously described, to further conversion in heating coil 25.

Fractionated vapors of the desired end-boiling point, preferably comprising conversion products within the boiling range of gasoline and of high anti-knock value, are withdrawn, together with uncondensable gas produced by the operation, 40 from the upper portion of the fractionator through line 45 and valve 46 to be subjected to condensation and cooling in condenser 47. The resulting distillate and gas passes from condenser 47 through line 48 and valve 49 to collection in 45 receiver 50. Uncondensable gas may be released from the receiver through line 51 and valve 52. The distillate is withdrawn from this zone through line 53 and valve 54 to storage or to any desired further treatment. When desired, a regulated portion of the distillate from receiver 50 may be recirculated, by well known means not shown in the drawing, to the upper portion of fractionator 21 to assist fractionation of the vapors in this zone and maintain the desired vapor 55 outlet temperature from the fractionator, thereby controlling the end-boiling point of the final light distillate product of the process.

The conditions in chamber 10 are preferably such that the vapors leaving said chamber will 60 contain a major portion or all of the gas oil fractions and will be substantially free of heavier fractions. When desired, separation of the heavier products from the gas oil and lighter vapors in chamber 10 may be improved by providing said 65 chamber with fractionating means of any well known form such as baffles, perforated pans, bubble trays, cooling coils, reboiling coils and the like, not shown.

The conversion temperature to which the high-boiling charging stock for the first described cracking stage of the process is subjected in the heating coil may range, for example, from 750 to 800° F., or thereabouts, preferably with a low superatmospheric pressure measured at the out- 70 75 75

let from the heating coil of from 150 pounds, or thereabouts, per square inch down to substantially atmospheric pressure. A pressure substantially equalized with or reduced relative to that employed in the heating coil may be utilized in the succeeding vaporizing chamber. A higher conversion temperature, preferably within the range of 900 to 1050° F., is preferred at the outlet from the heating coil of the second conversion stage of the process, preferably with a substantial superatmospheric pressure measured at this point of from 200 to 800 pounds, or more, per square inch. The heated products from this heating coil are preferably cooled by pressure reduction and by the introduction of high-boiling conversion products from the separator of the first conversion stage of the process to a temperature of the order of 800 to 900° F., or thereabouts, and a substantially reduced pressure of from 100 pounds, or thereabouts, per square inch down to substantially atmospheric pressure is preferred in the vaporizing chamber of this stage of the process and this pressure may be substantially equalized or somewhat reduced in the succeeding fractionating, condensing and collecting portions of the system.

As an example of one specific operation of the process of the present invention, as it may be practiced in an apparatus such as illustrated and above described, the charging stock is a Mid-Continent topped crude of about 23° A. P. I. gravity which is subjected in the heating coil of the first conversion stage to an outlet temperature of approximately 765° F., at a superatmospheric pressure of about 50 pounds per square inch. This pressure is substantially equalized in the succeeding vaporizing chamber from which liquid conversion products are withdrawn at a temperature of about 675° F., the vaporous products from this zone being condensed and supplied to the fractionator of the second conversion stage of the process from which the major portion thereof is withdrawn, together with reflux condensate formed in this zone, to the heating coil of this portion of the system. A conversion temperature of about 930° F., and a superatmospheric pressure of about 550 pounds per square inch is maintained at the outlet from the second heating coil. The unvaporized oil from the first conversion stage of the process is introduced into the stream of heated oil from the second heating coil after the pressure thereon has been reduced to approximately 40 pounds per square inch which is maintained in the succeeding vaporizing chamber. Residual liquid is withdrawn from this zone to cooling and storage and the vaporous products passed to the fractionator which is maintained at a pressure substantially equalized with that in the vaporizing chamber. This operation may produce, per barrel of topped crude supplied to the system, about 56% of motor fuel having an anti-knock value equivalent to an octane number of approximately 75, about 37% of residual oil suitable for use as fuel and about 600 cubic feet of uncondensable gas.

35 I claim as my invention:

1. A process for producing motor fuel which comprises subjecting hydrocarbon oil heavier than gas oil in a heating zone to relatively mild cracking conditions of temperature and pressure such as to produce gas oil therefrom, separating the thus treated oil into a residue heavier than gas oil and a distillate containing the gas oil, passing such distillate through a second heating zone and heating the same therein to higher cracking temperature than the oil in the first-mentioned heating zone.

75

ing zone to produce gasoline therefrom, then commingling the thus heated distillate with residue from the first-named cracking treatment, separating vaporous from unvaporized reaction products, and fractionating and condensing the 5 separated vapors.

2. A process for producing motor fuel which comprises subjecting hydrocarbon oil heavier than gas oil in a heating zone to relatively mild cracking conditions of temperature and pressure 10 such as to produce gas oil therefrom, separating the thus treated oil into a residue heavier than gas oil and a distillate containing the gas oil, passing such distillate through a second heating zone and heating the same therein to higher 15 cracking temperature than the oil in the first-mentioned heating zone to produce gasoline therefrom, then commingling the thus heated distillate with residue from the first-named cracking treatment, separating vaporous from 20 unvaporized reaction products, fractionating the separated vapors to condense insufficiently cracked fractions thereof, returning resultant reflux condensate to said second heating zone in admixture with an additional quantity of said 25 distillate, and finally condensing the fractionated vapors.

3. A process which comprises subjecting heavy hydrocarbon oil in a heating zone to relatively mild cracking conditions of temperature 30 and pressure, separating the heated oil in a separating zone into vapors and unvaporized oil and condensing the vapors, simultaneously passing a lighter oil through a second heating zone and heating the same therein to higher cracking temperature than the heavy oil in the first-mentioned heating zone, then discharging the thus heated lighter oil into a second separating zone and also introducing to this zone unvaporized oil from the first-named separating zone, separating the 35 resultant mixture in the second separating zone into vapors and residue and introducing the former to a fractionating zone, introducing to the fractionating zone condensate formed by the condensation of the first mentioned vapors and fractionating the second mentioned vapors in contact therewith independently of the first-named vapors, supplying liquid products from the fractionating zone to said second heating zone to constitute at least a part of said lighter oil, and 40 finally condensing the fractionated vapors.

4. A process for producing motor fuel which comprises subjecting hydrocarbon oil heavier than gas oil in a heating zone to relatively mild cracking conditions of temperature and pressure 55 such as to produce gas oil therefrom, separating the heated oil into vapors and a residue heavier than gas oil, subjecting the vapors to condensation to form a condensate containing the gas oil, introducing such gas oil condensate into a fractionating zone containing cracked vapors and fractionating the latter in contact with the condensate to condense insufficiently cracked fractions thereof, passing the resultant mixture of reflux condensate and gas oil condensate from 60 the fractionating zone through a second heating zone and heating the same therein to higher cracking temperature than the oil in the first-mentioned heating zone to produce gasoline therefrom, separating the resultant vapors and 65 introducing the same to the fractionating zone for fractionation in contact with said gas oil condensate, and separately condensing the vapors uncondensed in the fractionating zone.

5. A process for producing motor fuel which 75

- comprises subjecting hydrocarbon oil heavier than gas oil in a heating zone to relatively mild cracking conditions of temperature and pressure such as to produce gas oil therefrom, separating the heated oil into vapors and a residue heavier than gas oil, subjecting the vapors to condensation to form a condensate containing the gas oil, introducing such gas oil condensate into a fractionating zone containing cracked vapors and 5 separating the latter in contact with the condensate to condense insufficiently cracked fractions thereof, passing the resultant mixture of reflux condensate and gas oil condensate from the fractionating zone through a second heating zone 10 and heating the same therein to higher cracking temperature than the oil in the first-mentioned heating zone to produce gasoline therefrom, then commingling a substantial quantity of said residue with the thus heated mixture, separating 15 vaporous from unvaporized reaction products and introducing the former to the fractionating zone 20

for fractionation in contact with said gas oil condensate, and separately condensing the vapors uncondensed in the fractionating zone.

6. A process for producing motor fuel which comprises subjecting hydrocarbon oil heavier than gas oil to relatively mild conversion conditions of temperature and pressure such as to produce therefrom a major proportion of gas oil and a minor proportion of gasoline, separating gas oil and gasoline hydrocarbons thus formed 5 from residual oil heavier than gas oil and heating the same independently of and to higher cracking temperature than said heavy oil to produce additional gasoline from the gas oil and to increase the anti-knock value of said gasoline 10 hydrocarbons, then commingling the thus heated gas oil and gasoline hydrocarbons with said residual oil, separating the resultant mixture into vapors and residue, and fractionating and condensing the vapors. 15

JEAN DELATTRE SEGUY. 20
